CLAMP FOR CRUSHER JAWS

Joe McNeill, Marion, N. C., assignor to Marion
Machine Company, Marion, N. C.

Application July 31, 1939, Serial No. 287,651

4 Claims. (Cl. 113—99)

The invention relates to rock crusher jaw refacing, and particularly to means to enable the rebuilding of the dress face plates of crusher jaws by means of electric welding. Attempts have been made from time to time to accomplish such refacing without success, as the plates have varied in such manner that they could not be retained in the crusher. In consequence it has been usual to discard the plates after they become worn, and replace them with entirely new plates, making the maintenance of the jaw dress very expensive.

It is therefore an object of my invention to present means whereby the face plates of rock crusher jaws may be readily redressed by ordinary electric welding procedure, while the form of the plate is preserved with great certainty, enabling its replacement in the crusher and long continued use with repeated redressings.

Another aim of the invention is to present the means in an extremely simple form readily adapted to be produced by usual shop practice and production methods, and with such construction and manner of operation that it may be employed by the ordinary welders and workmen in crusher plants with a minimum likelihood of error in procedure, or loss by inaccuracy of the work or failure of the plates.

A still further object is to present a holder for plates while being redressed that will permit effective cooling of the plate while being welded, and will prevent warping transversely or longitudinally.

Another and further important object is to present a novel method of procedure in the welding of dress surfaces on such plates whereby the attainment of the ends in view as herein indicated is made possible.

Additional objects, advantages and features of invention reside in the construction, arrangement and combination of parts involved in the embodiment of the invention, as will be understood from the following description and accompanying drawings, wherein

Figure 1 is a top view of a machine constructed in accordance with my invention.

Figure 2 is a side view thereof partly in section.

Figure 3 is an end view of the machine.

Figure 4 is a cross section of the machine.

Figure 5 is an enlarged sectional view of one of the hold-down assemblies.

Figure 6 is a side view of a modified machine.

Figure 7 is an end view of the modification.

Figure 8 is a diagram showing temperatures, 55 vertical hydraulic ram 20, although other ap-

lengths and separation of medial planes of weld and plate and radius of curvature required.

There is illustrated a machine comprising lower and upper identical frames 10 and 11 assembled in mutually supporting relation, and being constructed from steel stock as two elements for convenience in production, particularly to facilitate welding of the joints. The upper frame will be described and the reference characters used with reference thereto applied to both. The frame consists of two main side beams 12 connected near the middle by two cross beams 13 while the ends of these side beams are connected by transverse angle end bars 14, two being used at each end, one at the upper side and the other at the lower side of the frame. Between the beams 12 spaced immediately outwardly of the beams 13, angle cross members 15 are fixed one at the top and one at the lower side of the frame 11, similar to the end beams 14, but shorter, so that they are fitted between the beams 12 for convenience in manufacture, while the beams 14 are extended flush with the outer sides of the beams 12. All junctions of attachment indicated between members of fixed relation in the frames are welded. At each end of the frame 11 there is thus formed a substantially square frame end portion. In each of these squares, longitudinal pairs of spaced anchor bars 16 are welded to the steel angles 14, there being at least two pairs, one pair adjacent each side beam 12 and spaced inwardly therefrom. These bars are substantially of the same cross sectional dimension as the beams 12, so that their upper and lower edges are at the same levels as the corresponding edges of the beams 12. Vertical spacers 17 may be welded between these bars at each end, and also extending to the horizontal flanges of the inner steel angle cross members 15. This completes the two frames.

The frames 10 and 11 are held in vertical alignment by outer guide and seat standards 17, one being located at each side, and each end of the frames. They may be attached to the lower frame and may extend in engagement with the outer sides of the frame 11, and may also be extended below the lower frame and formed as foot pieces 18, if desired, although other means to support the device may be utilized as found expedient. Each standard has a spacer or seat block 19 on its inner face, set snugly between the side beams 12, and cross beams 13 thereadjacent, to fix their spacing.

Centrally located within the frames, there is a vertical hydraulic ram 20, although other ap-

propriate pusher devices may be used, if found preferable. The cylinder 21 of this ram is set upon a base plate 22 beneath which there is located a foundation cross beam 23 connected by suitable hangers 24 with the top frame 11, although other expedients for connecting the cylinder to the two frames may be substituted if desired. The saddle 25 of the hanger extends under the beam 23 at the same level as the feet 18.

The piston rod 26 of the ram is provided with a cap and cross beam 27 of a length equal to the width of the frames 10 and 11 and normally transverse to these frames. In the present instance, consequently, the beam 27 sets above the frame 11. There are provided two blocking or supporting cross bars 28, which are set movably on top of the frame 11 as required, extending the full width of the frame, one at each end. At each end of the device a fulcrum block 29 is provided, one being set across each pair of anchor bars 16, each having a transverse rib 30 formed thereon, and resting at one end on this fulcrum there is a hold-down or jaw lever 31, the opposite end being a jaw 32, which is extended longitudinally inward for engagement over the end of a crusher plate 33 to be clamped, this plate being set on the blocking bars 28, as shown. The lever 31 is centrally formed with an enlarged eye or loop 34, and through this is engaged vertically a clamping bolt 35, set between the anchor bars of both frames 10 and 11, and having a head or nut 36 at the lower end resting against a washer 37 set against the lower edges of the anchor bars 16 of the lower frame, while on its upper end a nut 38 and washer are provided on top of the jaw lever 31. Tightening of the nuts 36 effects clamping of the plate 33, by the jaw 32.

In Figures 6 and 7 the frame construction is modified to the extent that a top frame 40 is used, similar to the frame 11 for the most part, and the ram 21 is similarly set centrally beneath the frame 40. Instead of the lower frame 10, truss bars 39 and 39' are provided, extended diagonally upward from a base beam 23' similar to the one 23 and similarly located. The frame 40 differs in that two anchor beams 42 are incorporated in the frame as side members, one pair of these beams at each side, the two beams in each pair being spaced sufficiently to receive the anchor bolts 43 therebetween, which may be shorter than the bolts 35 before described but otherwise are similarly engaged with the frame and with the hold-down device as first described, which is unchanged. This frame may, if desired, include a number of short longitudinal bars 44 inwardly of the bars 42 spaced transversely of the frame and secured to the transverse angles 14' and cross beam 13', which are incorporated in the same relation on the frame 40 as on the frame 11, except that the inner cross beams stop at the inner bars 42.

There are two truss bars 39 at each side of the frame and two truss bars 39'. The former may be formed in one piece if desired, welded at its middle to the end of the cross beam 23', while its end portions are bent upwardly and welded to the outer sides of the outer bar 42.

The truss bars 39' may be similarly formed but are welded to a bed plate 45 set between the base of the cylinder of the ram and the beam 23'. The cross beams 23 and 23' may be formed of channel stock, if desired.

In the use of this invention it will be understood that its purpose is to establish a strain in the work whereby the latter will be held in a

definite shape while ribs are welded thereon and thereby counteract the permanent distortion of plates which occurs under ordinary welding operations.

Heretofore, in welding such plates, it has been attempted to weld the new ribs on starting with a cold plate. It will be appreciated that the crusher jaw face plates have a multiplicity of parallel ribs similar to the surface of the old fashioned washboard. When it has heretofore been attempted to renew these ribs after they have worn away, electrical welding has been employed, using an applicator bar the fusing of which on the work unites the fused material with the plate and by progression of the weld along the proper lines forms ribs which as nearly as practicable approximate the original ribs. Such applied or built-up welded ribs have been found to be very hard and serviceable but the irregular warping of the plates has prevented the successful continuance of the practice heretofore. In these prior attempts, operating on a cold plate held by ordinary work-holding devices, the plate becomes progressively hotter with each rib formed, and when the plate has cooled, it is found curved out of proper shape, and this curving is irregular, there being an irregular distortion.

It will be appreciated that at the start of such prior operation the plate will be relatively cool, but the rib material and immediately adjacent portion of the plate will be fused at a high temperature. The added weld material and united part of the plate will be liquid, then plastic and will rapidly cool, and contract, but will not set up stresses as it cools until at some "set" temperature the material will have "hardened" sufficiently to retain strain due to its tendency to contract more than the plate increases due to its being cooled to a greater extent than the plate body, and stresses result which tend to bend the plate to a position different from that which it would assume if merely heated and cooled without the applied material. Attempts to heat the plate prior to the welding have not met with success since similar results follow, if in lesser degree.

It will be appreciated that the principal effective stresses causing the difficulties under the old practice are those stresses developed longitudinally of the ribs, since transversely of the ribs the contractile effect of each rib is disassociated and disconnected from the similar effects of the next adjacent rib, and the slight local transverse stresses do not operate to materially affect the shape of the plate. The cumulative contractile action of the rib longitudinally, increasing with each unit of length, becomes a serious force acting on one side of the plate. Due to the fact that the body of the plate becomes hotter with each rib applied, the relative difference in effect between the rib portions at one part of the plate and those at another later welded, make for great irregularity in the deformation. Also the time element involved in the welding technique of the welder, which is apt to be fast at one time and slower at another time, have a material effect on the nature of the distortion caused, it is thought. Whatever the causes, experience has demonstrated that the plate whether worked on cold or hot, and held by ordinary expedients, will usually be distorted so seriously as to be unfit for service in a crusher.

By the use of my invention it has been pos-

sible to hold the plate in a definite fixed shape while the welding of the ribs thereon is carried out, and also by one method to deform the plate in a direction the opposite of that in which the applied ribs tend to act when cooled so that when released the elastic recovery of the plate material and the contraction of the applied material coincide in effect, with the result that the plate simply resumes its initial normal form. The compensatory strain required may be mathematically calculated, as shown below. It must be arranged that the length of the added weld material at this "set" temperature will be such that when its temperature falls to that of the main plate, the weld shall have contracted to equal the length of the plate, in which case the plate and weld will be flat and free of strain. Consequently, the "face" of the plate must be lengthened relative to the body of the plate while the weld material is applied and returned to its normal unstrained position afterward.

This is accomplished by bowing the plate to an arc of a circle, according to the diagram of Figure 8, so that the "length of the weld" L_w is on a longer radius than the "length of the plate" L_p . The problem is to discover the required radius of curvature R , which will effect the required increase in length of the face of the plate.

Although a complex distribution of temperatures, and an unknown position of neutral planes will be encountered in practice, which might prevent solution even by intricate mathematical treatment, we may approximate the problem by using the average temperature of each element, the weld and the plate, and assuming that the central plane of each will be independently responsive to the average temperature thereof.

The required increment in length of the weld at its "set" temperature which will permit it to shrink down to the length of the plate when temperatures are equalized is equal to:

$$(T_w - T_p) L_p C$$

where C is the coefficient of expansion, and $(T_w - T_p)$ is the temperature difference between weld and plate.

Then L_w , the required length of weld at its "set" temperature will be:

$$L_w = L_p + (T_w - T_p) L_p C$$

Referring to Figure 8 the angle subtended by the arc of the plate may be measured in radians, and termed "A."

Then:

$$A = \frac{L_p}{R} = \frac{L_p + (T_w - T_p) L_p C}{(R + D)}$$

Where R is the radius of curvature of the medial plane of the plate, and D is the distance therefrom to the medial plane of the weld.

Solving for R :

$$L_p R + L_p D = L_p R + R (T_w - T_p) L_p C$$

and

$$R = \frac{D}{C(T_w - T_p)}$$

It will be at least qualitatively apparent from the foregoing analysis that the required radius of curvature of the plate during the welding operation is dependent upon three variables: the coefficient of expansion of the metal, which is substantially constant, the temperature differential between the main plate body and the weld at the instant the weld retains permanent strain, and the separation between the plate and weld, which is approximately the thickness of the plate, in

practice. The latter two factors are somewhat dependent, and it will be sufficient to make a tabulation of the required radius of curvature for the several thicknesses of plates which will be handled. A suitable guage to measure the radius of curvature while the plate is in the press may be formed of a bar having fixed end projections or rests, and a central probe which actuates a dial calibrated to read the radius of curvature directly when the bar guage is pressed against the lower side of the plate so that all three rests are in contact with the plate. If the plate is normally bowed, the guage should be "zeroed" against the unstressed plate.

To simplify the work for ordinary workmen, it may be determined by laboratory or other demonstration what definite hydrostatic pressure in the ram 16 is required to hold a given plate in the desired form shown by an equation applied to the particular plate, and as there is a fixed standard for the material of such plates, and uniformity of size, it will be sufficient to give a table of pressures to be applied to a definite range of plate sizes and materials. For a given plant this would be probably reduced to a single pressure suitable for the crusher face plates of the plant which it may be assumed will standardize on a single source of plate manufacture, and will have crushers with the same size plates throughout. In one standard facing plate a total pressure of 150 tons approximately have been found necessary in the ram which would correspond to a guage pressure in the neighborhood of 5,000 pounds to the square inch, these readings being with instruments of ordinary use not ordinarily tested for accuracy, but indicating substantially high pressures required. The plate on which this pressure was used was one measuring 20 by 24 inches, and of an average thickness of $3\frac{1}{4}$ inches. The thickness on any normal transverse plane was uniform from one side to the other, except for the irregularities of the ribs.

It is an advantage of my invention that in cases where the ribs are worn more at one part than at another, and the build-up is required less at one part than at another, the compensatory effect is properly manifest equally well as for plates which require the replacement of the ribs throughout their length. The degree of heating of the plate in the welding operation has been found to be relatively unimportant at the temperatures encountered in such work.

I claim:

1. A machine of the character described consisting of a top frame having at least two pairs of parallel bars, the pairs spaced apart in a common plane, a plurality of bolts set between the bars of each pair universally slideable in a plane normal to the first mentioned plane, means to anchor the bolts below the bars, a transverse fulcrum member set over the bars adjacent each bolt, a hold-down jaw loosely slideable on each bolt and having a recessed end to receive the fulcrum member therein and projecting oppositely from the bolt to engage over a piece of work, a cylinder having an axis normal to the said plane below the frame, a piston therein and a plate engaging member thereon arranged and constructed to engage a plate in opposition to said hold-down jaws, and means to supply fluid pressure to said cylinder.

2. The structure of claim 1 in which said top frame is duplicated therebelow, said bolts being engaged through both frames, said means to anchor the bolts being engaged with the under

side of the lower frame, spacers between the outer parts of the frames, and both frames being connected to said cylinder.

3. A machine of the character described consisting of a bed element, fulcrum blocks on the bed element, a jaw supported by each fulcrum and projecting inwardly over the bed element, transverse supports on the bed element positioned to lie beneath respective end portions of a plate and spaced inwardly of the projecting portion of the jaws, means between each fulcrum and transverse supports for forcibly drawing and holding the projecting portion of the jaws into engage-

ment with a plate positioned on the transverse supports, and a pushing device constructed to engage the central portion of a plate held by the jaws and transverse supports to bend the same for the purposes described.

4. The machine as set forth in claim 3 in which each jaw consists of a body having an opening therethrough, a bolt carried by the bed element and positioned outwardly of the work and extended through the opening, said jaw further having a groove to receive the fulcrum therein, and a nut on the bolt to hold the jaw down.

JOE McNEILL.
